UNITED STATES PATENT OFFICE.

GEORGE L. DIXON, OF EAST SAN GABRIEL, CALIFORNIA.

GAS STOVE WITH REFLECTING BASE.

Application filed August 16, 1920. Serial No. 403,633.

To all whom it may concern:

Be it known that I, GEORGE L. DIXON, a citizen of the United States, residing at East San Gabriel, in the county of Los Angeles 5 and State of California, have invented a new and useful Gas Stove with Reflecting Base, of which the following is a specification.

This invention relates to a gas stove having an outlet for heat at the lower end of 10 the casing and provided with a reflector therebeneath for the double purpose of protecting the surface on which the stove sets and reflecting the heat outwardly to the zone surrounding the lower portion of the stove.

15 An object of the invention is to make provision for effecting maximum heating of the zone surrounding the lower portion of the stove adjacent the floor on which the stove rests.

20 Another object is to provide a reflecting base capable of being employed with various types of stoves as a base therefor.

The accompanying drawings illustrate the invention:

25 Figure 1 is a side elevation of a stove embodying the invention.

Fig. 2 is an enlarged elevation mainly in vertical mid-section of the lower portion of the stove shown in Fig. 1.

30 Fig. 3 is a fragmental sectional elevation cutting through one of the legs to show the connection between said leg and the base.

Fig. 4 is a plan view of my new reflecting base detached.

35 Fig. 5 is an elevation of Fig. 4 from the front or either side thereof.

Fig. 6 is a reduced plan section on line indicated by X⁶—X⁶, Fig. 2.

There is provided a casing 1 open at its 40 lower end as clearly indicated at 2, said casing being in the form of a smooth cylinder with the exception of top and bottom flanges 3, 4, respectively, which are curved outwardly and downwardly and enlarged 45 the diameter of the casing at its ends. The lower portion of the casing 1 forms a combustion chamber 5 in which is positioned a burner 6 of any suitable type. The burner 6 is supplied with fluid fuel through a pipe 50 7 provided with a valve 8.

The burner 6 is positioned immediately beneath a hot air chamber 9 which rests upon legs 10 that in this instance are hollow, the bores 11 of the legs communicating with the 55 chamber 9. The legs 10 are provided adjacent their lower ends with openings 12 in

their inner sides so as to admit air to the bores 11 which in turn admit the air to the hot air chamber 9.

The legs 10 are provided with shoulders 13 60 and resting upon said shoulders is a deflector or shield 14 provided centrally with an opening 15 through which the burner 6 projects. The opening 15 is of larger diameter than the adjacent portion of the burner so that 65 air can pass upwardly through the shield 14 adjacent the burner. At the periphery of the shield 14 are formed downwardly and outwardly slanting deflecting flanges 16 which aid in deflecting the heat passing 70 downwardly through opening 2 outwardly, but it is to be understood that the flanges 16 may be omitted, if desired. The lower ends of the legs 10 are formed with inwardly extending flanges 17, one of said 75 flanges being shown in Fig. 3 of the drawings.

The flanges 17 rest upon the upper surface of the reflecting base 18 and may, if desired, be affixed to said base by any suitable 80 fastenings. In this particular instance each fastening comprises a stove bolt 19 passing through the base and through the flanges of the legs as clearly shown in Fig. 3.

The legs 10 rest upon the peripheral portion 20 of the base 18 and said peripheral portion is flat. The more central portion of the base rises in an upwardly reduced or conical portion 21 which, in this particular instance, is slightly concave inwardly. It 90 is to be understood that the base 18 may be circular, square or of any other desired outline, it being shown in the drawings substantially square, with the corners slightly rounded.

When the fuel is ignited at the burner 6 and the stove is in operation, air passes through the openings 12 upwardly through the legs to the chamber 9 and is heated. The lower portion of the chamber 9 forms a downwardly reduced radiator 22, which serves to spread the flame from the burner and also to radiate heat downwardly through the opening 2 on to the base 18.

The base 18 has a highly polished mirror-like upper surface which functions to reflect the heat outwardly and upwardly, said base absorbing practically no heat. The conical portion 21 of the base forms therebeneath an air space 23 which further protects the 110 surface on which the stove rests from any heat absorbed by said conical portion.

I claim:

In a stove, the combination of a casing open at its lower end, a hot air chamber in the lower portion of the casing, a burner 5 beneath the hot air chamber, hollow legs communicating with and supporting the hot air chamber and provided at their lower ends with flanges and with openings above the flanges, and a one piece sheet metal base

having a flat peripheral portion secured to 10 the flanges, said base also having an upwardly reduced portion near its center.

Signed at Los Angeles, California this 9th day of August, 1920.

GEORGE L. DIXON.
